UNITED STATES PATENT OFFICE.

JOZefa KECZUR, OF WEST SELKIRK, MANITOBA, CANADA.

DESIGN FOR A COMBINATION CHIPPED-GLASS FRAME AND MIRROR.

Application filed December 12, 1922. Serial No. 4,583. Term of patent 7 years.

To all whom it may concern:

Be it known that I, JOZefa KECZUR, a citizen of Ukraine, residing at West Selkirk, in the Province of Manitoba and Dominion of Canada, have invented a new, original, and ornamental Design for Combination Chipped-Glass Frame and Mirror, of which the following is a specification, reference being had to the accompanying drawing, forming part thereof.

The figure is a front elevational view of a combination chipped glass frame and mirror, showing my new design.

I claim:—

The ornamental design for a combination chipped glass frame and mirror, as shown.

JOZefa KECZUR,
